UNITED STATES PATENT OFFICE.

TOFIC A. TAHAN, OF UNION CITY, NEW JERSEY.

LUG-STRAP SUPPORT.

Application filed January 8, 1927. Serial No. 159,857.

This invention relates to a lug strap support, and particularly to a construction adapted for application to the picker stick or staff of a loom by which the loop extending from the actuating bar is connected to said stick.

In the operation of such constructions the movement of the bar in opposite directions imparts a pressure or impact to the connecting means for the support upon the stick resulting in a frequent loosening thereof which requires replacement of the support in a new position. It has also been found desirable to provide a construction of support which may be readily adjusted vertically upon the stick, reversed in position thereon, or used in cooperation with a similar support at the opposite side of the stick. Such a field of location and adjustment of the support has not been possible in prior constructions so far as I am aware and the present invention is designed to provide a simple construction capable of the improved functions and of a rigid connection with the stick when secured thereto.

It has also been found important to avoid the direct bearing of the leather loop from the actuating bar against the metallic body of the support, and this has been effected by a novel construction in which the portion of the support surrounding the loop is offset from the stick and provided with bearing surfaces engaging the stick at one side and having an antifriction support for the vertical edges of the loop which contacts therewith.

The invention has for an object to provide a novel and improved construction including a supporting plate having an outwardly disposed shoulder at its upper end with a strap supporting face and an offset guard from the outer portion of said shoulder having an inwardly disposed projection comprising a bearing at the upper edge of the lug strap.

Another object of the invention is to provide a longitudinally slotted supporting plate carrying at its upper portion an offset guard and combined with a clamping plate disposed at the opposite side of the stick and connected with the retaining plate by means of an attaching bolt or similar device.

A further object of the invention is to provide a retaining plate having a longitudinally disposed flange at one side and a

curved shoulder at the upper end of said flange from which an offset guard extends and is provided with an inwardly disposed curved bearing lug contacting with the face of the stick, together with means for rigidly securing the retaining plate in position.

Other and further objects and advantages of the invention will be hereinafter set forth and the novel features thereof defined by the appended claims.

In the accompanying drawing:

Figure 1 is an elevation showing the connection between the stick and strap;

Figure 2 is an enlarged elevation from the opposite side from Figure 1 with part of the stick broken away;

Figure 3 is a detail edge view;

Figure 4 is a section on the line 4—4 of Figure 3; and

Figure 5 is a similar view of a modified application of two of the supports.

Like reference numerals designate corresponding parts throughout the several figures of the drawing.

Referring to the drawing, A designates the picker stick or staff conventionally used in loom apparatus and B the actuating or connecting rod from which the strap C extends to embrace the stick. The present invention relates particularly to means for supporting this strap in its relation to the stick so that it may be free for the necessary oscillatory movement incident to the movement of the stick in a curved path and a substantially horizontal movement of the actuating bar. For this purpose the support is provided with a plate 10 adapted to engage a face of the stick and formed with a longitudinally extending flange 11 at one edge which engages an angular face of the stick so as to prevent an oscillatory movement of the plate upon its connecting means.

At the upper portion of the supporting or retaining plate 10 a shoulder 12 extends outward therefrom and is formed with an inclined or curved bearing surface 13 from which a guard plate 14 extends longitudinally of the stick and is provided at its upper end with an inward projection or lug 15 having a curved or inclined inner face 16 adapted to engage the edge of the strap C in its movement relative to the stick. Such a construction removes the strap from rubbing or abrasive contact with the metal of the support and permits the same to be freely

operable upon the body of the stick surrounded thereby. This is accomplished by offsetting the guard plate and providing inwardly extending bearing surfaces which 5 contact with a side of the stick.

In the use of such a support it is frequently desirable to adjust the position thereof vertically upon the stick in order to secure the most efficient positioning of the loop 10 relative thereto and for this purpose the retaining plate 10 is provided with a longitudinal slot 17 extending parallel to the flange 11 and through which a retaining device such as the bolt 18 is passed. This bolt 10 being mounted in the stick permits the vertical adjustment of the support thereon and for the purpose of retaining the support 15 against accidental slipping or play it may be formed with a plurality of teeth or pins 20 as indicated at 19 which are embedded in the wood of the stick when the bolt is tightened. Cooperating with the head 20 of the bolt I also use a clamping plate 21 having angular flanges 22 at each side which embrace the 25 stick A and retain the plate against rotative movement thereon.

The construction of the support is such that it may be disposed at either side of the stick or reversed in position thereon, for instance, as shown by dotted lines at 23 in 30 Figure 3, in which case the position of the holder is transferred from one side of the stick to the other. Under some conditions of use it may be desirable to provide the supports upon opposite faces of the stick and such result can be accomplished by the construction shown at 23 in Figure 3 or by securing the supports by the same attaching means as indicated by the section in Figure 40 5 wherein the retaining plates 10 are parallel to each other and secured by a device as indicated at 24. In such an arrangement the second support used replaces the clamping plate 22 indicated in Figure 3. 45 The operation of the invention will be apparent from the foregoing description from which it will be seen that the construction provides for a wide field of adjustment of the support upon the picker stick to provide 50 for substantially all desired positioning

thereof relative to the strap and further form a guard having bearings for the vertical movement of the strap and retaining the same against lateral displacement. In such a construction it is particularly desirable to 55 provide against any movement of the support upon the stick, and for that reason the structure of the retaining plate with its flange is provided in connection with the guard plate carried by the upper end 60 thereof.

While the specific construction of the several parts has been shown and described, the invention is not confined thereto as changes and alterations may be made therein within 65 the spirit of the invention as defined by the following claims.

Having thus described my invention, what I claim as new and desire to secure by Letters Patent of the United States, is:— 70

1. A lug strap support comprising a retaining plate having an outwardly disposed shoulder at its upper end with an inclined supporting face, an offset guard from the outer portion of said shoulder terminating 75 in a free end and having an inwardly disposed lug at the upper end of the guard engaging a side of a stick but free from the edges thereof and formed with a bearing face for a lug strap, and means extending longitudinally of the plate below said shoulder for retaining the plate against lateral movement upon a stick.

2. The combination with a picker stick, of a slotted retaining plate having an angularly 85 disposed longitudinal flange at one edge and an outwardly extending shoulder at its upper end with a curved bearing face, an offset guard from the upper portion of this shoulder terminating in a free end and having 90 an inwardly disposed lug with a curved bearing face for a strap, a clamping plate upon the opposite face of the stick from the retaining plate and formed with angular flanges 95 to engage the edges of said stick, and means cooperating with the clamping and retaining plates to permit the longitudinal adjustment of the latter upon the stick.

In testimony whereof I affix my signature.
TOFIC A. TAHAN.
